CLAIM

We claim the ornamental design for a surface mountable loudspeaker, as shown and described.

DESCRIPTION

FIG. 1 is a front and right side perspective view of the surface mountable loudspeaker showing our new design;

FIG. 2 is a top plan view thereof;

FIG. 3 is a front elevation view thereof;

FIG. 4 is a right side elevational view thereof;

FIG. 5 is a left side elevational view thereof;

FIG. 6 is a rear elevation view thereof;

FIG. 7 is a bottom plan view thereof;

FIG. 8 is a front and right side perspective view of a second embodiment of the surface mountable loudspeaker showing our new design;

FIG. 9 is a top plan view thereof;

FIG. 10 is a front elevation view thereof;

FIG. 11 is a right side elevational view thereof;

FIG. 12 is a left side elevational view thereof;

FIG. 13 is a rear elevational view thereof; and,

FIG. 14 is a bottom plan view thereof.

The broken line showing of front grill, mounting surface, front air vents and mounting brackets is for illustrative purposes only and forms no part of the claimed design.
